MAGAZINE CABINET HAVING TILT TABLE RECEPTACLES

Filed Sept. 15, 1948

Fig. 5.

A technical diagram showing a cross-section of a structural joint. The top part features a horizontal ribbed plate with a central U-shaped cutout. The cutout is labeled '66' on the left and '45a' on the right. The base of the U-cutout is labeled '67' on the left and '68' on the right. Below the plate is a hatched rectangular area, and to its right is a vertical label '27a'.

MAGAZINE CABINET HAVING TILT TABLE
RECEPTACLES

Clair C. Gardner, Rockford, Ill.

Application September 15, 1948, Serial No. 49,394

10 Claims. (Cl. 312—252)

1

This invention relates to a magazine cabinet, and has for its principal object the provision of an easily rotatable and openable and closable cabinet, having a plurality of magazine receiving racks provided therein in circumferentially spaced relation, adapted to contain different magazines, the names of which may, if desired, be placed on suitable legends printed on the outside of the cabinet, so that any one of the magazines is instantly accessible for removal when the cabinet has been turned to the correct position and opened, and yet all of the magazines are concealed from view when the cabinet is closed, thus avoiding the unsightliness commonly associated with many conventional magazine racks, in which the magazines are left exposed, and protecting the magazines from dust and the likelihood of soiling due to handling by little children.

A salient feature of the present device is the provision of door elements that are arranged to be swung outwardly from a closed position relative to the body of the cabinet, each being slidably connected on the inner side with a receptacle element for a magazine, one of these slidably connected elements being hinged relative to the cabinet and the other element being operatively connected with a sleeve slidable on the lamp standard, on which the cabinet is mounted for rotation, in such a way that when the sleeve is moved endwise in one direction the door is swung open and relative sliding movement occurs between the door and the receptacle to expose the upper end of the magazine for easy removal, the door and receptacle being returned to their normal relationship in the closing of the door upon movement of the sleeve endwise in the opposite direction. In the present case, the receptacles are hinged on the cabinet and the doors slide up and down thereon, downwardly in opening and upwardly in closing.

The invention is illustrated in the accompanying drawing, in which—

Fig. 1 is a vertical section through a cabinet made in accordance with my invention, showing the doors closed;

Fig. 2 is a view similar to Fig. 1, but showing the door opened and slid down to expose a magazine or magazines in the receptacle;

Fig. 3 is a section on line 3—3 of Fig. 1 with a portion of the receptacle broken away to show the sliding connections between the door and receptacle;

Fig. 4 is a plan view of Fig. 3;

Fig. 5 is an enlarged sectional detail on line 5—5 of Fig. 3, and

2

Fig. 6 is a detail on line 6—6 of Fig. 1.

The same reference numerals are applied to corresponding parts throughout the views.

Referring to the drawing, the lamp forming a part of this combination device comprises a tubular standard 9, on a base 10, through which wires are extended in the usual way to the socket for the electric light bulb. The cabinet 15 is rotatable about the standard 9 as an axis, the top 16 and bottom 17 having center holes 18 and 19 through which the standard 9 extends, and the bottom 17 resting on a spool 20, which spaces the cabinet in a predetermined elevated relation to the base 10. 21 is a metal collar suitably secured to the top 16 of the cabinet at the center, through which a sleeve 22 is slidably in telescoping relation to the standard 9. A knob 23 is preferably provided on the upper end of the sleeve 22 to facilitate up and down movement thereof. The sleeve 22 is pivotally connected at its lower end with rocker arms 57, as at 58, one of these arms being provided for each of the plurality of door and receptacle assemblies, and the arms being forked at their outer ends 59 and 25 pivotally connected, as at 60, to the inner sides of the doors 27a. The rocker arms 57 are adjustable in length, as indicated at 61, so as to enable accurately fitting each door to close properly. Links 62 pivoted to the bottom of the cabinet at 63 provide oscillating support at their upper ends for the rocker arms 57, as indicated at 64. The receptacles 45a, which are hinged at their lower ends, as at 65, to the bottom of the cabinet, have the door panels 27a slidably mounted thereon, as by means of screws 66 on the doors entered in vertical slots 67 provided in outwardly projecting beads 68 formed on the front walls of the sheet metal bodies of the receptacles 45a, these beads serving to space the door panels from the front of the receptacles and provide low friction sled runners or skids on which the door panels may slide up and down easily and noiselessly. Three beads are provided on each receptacle front wall, as appears in Fig. 3, spaced and arranged in the manner shown so as to avoid likelihood of any binding action. The front and side walls of each receptacle are formed from a single piece of sheet metal, the side walls being bent inwardly at the back, as at 69, and suitably fastened to the wooden back wall 70, and there being also a wooden bottom wall 71 suitably fastened to the lower end of the back wall and to the rest of the receptacle. The back wall 70 projects high enough to nearly reach the top 16 of the cabinet and shut off the view into the interior of the cabinet when the doors are opened.

and the receptacles swung outwardly to operative position, as in Fig. 2. It is clear from Figs. 1 and 2 that to slide open the doors and swing out the receptacles one need only raise knob 23, to raise sleeve 22 as in Fig. 2. Upward movement of sleeve 22 is shown as positively limited by a flexible chain 72 attached at one end to the sleeve and at its other end to a bracket 73 fastened to the bottom 17 of the cabinet. This same bracket cooperates with a radially projecting lug 74 10 provided on the lower end of sleeve 22 to lock the cabinet doors closed automatically when the sleeve 22 is moved down as far as it can go, the lug 74 being then engageable in a notch 75 provided in the vertical leg of the bracket, as shown in Fig. 6. To unlock and open the cabinet, one merely turns and lifts knob 23. The top of the vertical leg of bracket 73 is inclined, as at 76, so as to guide the lug 74 automatically toward the notched side of the bracket, the sleeve 22 normally occupying a position of rotation wherein the lug 74 naturally enters the notch 75, and there being enough give and resilience in the structure and looseness in the various joints to permit the sleeve 22 to be turned through such a small angularity in locking and unlocking the cabinet.

The operation of this cabinet is believed to be clear from the foregoing description. Although, of course, the cabinet 15 is intended primarily for storage of magazines, it will be apparent that there is adequate space left inside the cabinet for storage and safe keeping of other things, and with that thought in mind the screws or pins 60, which pivotally connect the arms 59 to the doors 27a, may be made easily removable to permit swinging any one of the doors 27a outwardly from the opened position, shown in Fig. 2, so as to permit placing articles in or removing articles from the inner confines of the cabinet. It should be evident that with the present construction it requires very little effort to open and close the doors, the receptacles 45a which are sometimes loaded with heavy magazines being merely oscillated, the door panels, which are much lighter than the loaded receptacles, being the parts that are slid up and down. In this construction a locking action at one extreme of movement is sufficient, there being no need of locking the doors in lowered position. It is also considered to be rather advantageous that in this construction the magazines always stay on their original level below the top of the cabinet throughout the operation, there being nothing raised above the level of the cabinet top, the slidable door panels being slid downwardly in opening.

It is believed the foregoing description conveys a good understanding of the objects and advantages of my invention. The appended claims have been drawn to cover all legitimate modifications and adaptations.

I claim:

1. A device of the character described, comprising a base, a standard supported thereon, a cabinet supported on said standard and having a plurality of receptacles on the outer sides thereof which are hinged to the cabinet by their lower portions to swing outwardly to afford access to magazines and the like placed therein, closures for the cabinet slidable up and down on the outer sides of said receptacles, and a central operator for said receptacles and closures operatively connected with the closures and movably mounted on said standard and arranged to swing the re-

ceptacles outwardly and lower said closures, and vice versa.

2. A device as set forth in claim 1, including means for releasably locking the central operator in an extreme position.

3. A device of the character described, comprising a base, a standard supported thereon, a cabinet rotatably supported on said standard for storage of magazines and the like and having a plurality of magazine receptacles hinged and mounted in said cabinet and oscillatable to and from a magazine dispensing position, closures on the outer sides of said cabinet slidably connected to said receptacles for up and down movement, 15 a sleeve serving as a central operator for said closures mounted in telescoping relation to said standard and movable endwise and rotatively relative thereto, and rocker elements pivotally mounted intermediate their ends on supports 20 oscillatably mounted in the cabinet, said rocker elements providing operating connections between said sleeve and said closures, whereby said closures are opened and closed by endwise movement of said sleeve and the receptacles are moved 25 to and from dispensing position.

4. A device of the character described, comprising a vase, a standard supported thereon, a cabinet rotatably supported on said standard for storage of magazines and the like and having 30 a plurality of receptacles therein for the magazines hinged by their lower end portions to the cabinet to swing outwardly to a magazine dispensing position, closures for the cabinet attached to and slidably up and down on the outer 35 sides of said receptacles, a sleeve serving as a central operator for said closures mounted in telescoping relation to said standard and movable endwise and rotatively relative thereto, and operating connections between said sleeve and said 40 closures, whereby said receptacles are swung outwardly and the closures are simultaneously slid downwardly by endwise movement of said sleeve in one direction, and vice versa.

5. A device of the character described, comprising 45 a base, a standard supported thereon, a cabinet supported on said standard and having a plurality of doors on the outer sides thereof which, when opened, afford access to magazines and the like stored in the cabinet, receptacles for 50 magazines and the like hinged in the cabinet and having said doors slidably mounted on the outer sides thereof, and a single operating means operatively associated with all of said receptacles and doors to swing all of said receptacles simultaneously outwardly to magazine dispensing positions and slide said doors in one direction in the 55 movement of said operating means in one direction, and vice versa.

6. A device of the character described, comprising 60 a base, a standard supported thereon, a cabinet supported on said standard and having a plurality of doors on the outer sides thereof which, when opened, afford access to magazines and the like stored in the cabinet, receptacles for 65 magazines and the like hinged in the cabinet and having said doors slidably mounted on the outer sides thereof, and a single operating means operatively associated with all of said receptacles and doors to swing all of said receptacles simultaneously outwardly to magazine dispensing positions and slide said doors in one direction in the 70 movement of said operating means in one direction, and vice versa, said cabinet being rotatable relative to said standard to position any one of said 75 receptacles adjacent an operator's station, and

said operating means being so arranged that it is operative from the operator's station with equal facility with said cabinet in any position of rotation.

7. In a rotatable filing device of the character described, a supporting standard, a cabinet rotatable thereon as an axis and having a receptacle on the radially outer side arranged to swing outwardly to afford access to articles placed therein, a closure slidable endwise with respect to said receptacle, and a central operator operatively connected with the closure and movably mounted on said standard and arranged to swing the receptacle outwardly and move the closure endwise simultaneously.

8. A device as set forth in claim 7, including means for releasably locking the central operator in an extreme position.

9. In a cabinet of the character described, a housing having an opening, a receptacle hinged at its lower end on said housing partially to close said opening, a closure attached to and slidable up and down on the outer side of said receptacle, a throw-out arm pivoted intermediate its ends with respect to the receptacle and at its outer end 25

to the closure to swing the receptacle outwardly and slide the door downwardly, and means operable from outside said housing and connected with the inner end of said throw-out arm to rock the same.

10. A device as set forth in claim 3, wherein the rocker elements are of adjustably fixed length, whereby to enable accurately fitting each closure to close properly.
